UNITED STATES PATENT OFFICE.

SAMUEL W. SHOREY, OF BOSTON, MASSACHUSETTS.

IMPROVEMENT IN MACHINES FOR ATTACHING BUTTONS, &c.

Specification forming part of Letters Patent No. 173,141, dated February 8, 1876; application filed August 12, 1875.

To all whom it may concern:

Be it known that I, SAMUEL W. SHOREY, of Boston, in the county of Suffolk and State of Massachusetts, have invented a certain new and useful Improvement in Machine for Attaching Buttons to Clothing, Boots and Shoes, &c., of which the following is a description sufficiently full, clear, and exact to enable any person skilled in the art or science to which my invention appertains to make and use the same, reference being had to the accompanying drawing, forming a part of this specification, in which—

Figure 1 is an isometrical perspective view; Fig. 2, a vertical longitudinal section taken on the line *x*; and Figs. 3, 4, and 5, sectional views.

Like letters of reference indicate corresponding parts in the different figures of the drawing.

My invention relates to mechanism for attaching buttons by means of metallic fastenings; and consists in a novel construction and arrangement of the parts, as hereinafter more fully set forth and claimed, by which a simpler, cheaper, and more effective device of this character may be produced than is now in ordinary use.

The nature and operation of my invention will be readily obvious to all conversant with such matters from the following description:

In the drawing, *A* represents the body of the machine, which is supported upon the legs *c c*, and carries at its upper end the cup-shaped socket-piece *C*. Pivoted at *g* to the body *A* there is a lever, *B*, to one end of which is attached the spring *a*, carrying the bed-piece *N*, the short arms of the body and lever forming, respectively, the upper and lower jaws of the machine. Fitted to work in the socket-piece *C* there is a stock, *D*, its form being that of an inverted conical frustum, to the upper part of which, at *F*, is pivoted the lever or handle *E*. The stock *D* is kept in position by means of the bolt *S*, which also acts as a twister, and is screwed into the bottom of the same, passing upwardly through the short arm of the body *A* and lower part of the socket-piece *C*. The bolt is drilled through its center to receive the vertical plunger *H*, and is provided with the shoulder *m*, which fits into a rabbet

in the lower side of the upper jaw. The lower surface of the bolt *S* is extended by means of the plate *L*, which is attached by one end to the body *A*, its opposite end being nicely fitted around the bolt. An elastic supporting-plate or retainer, *M*, is secured to the lower side of the upper jaw by the screw *p*, having a slot in its free end, (not shown,) in which the shank of the button is inserted. A rod, *P*, has its upper end concaved or curved, as seen at *i*, and is provided with the head *h*. Around the plunger *H* there is a coiled spring, *n*, one end of which rests upon the upper end of the bolt *S*, and the other against the under side of the head *h*, and which acts expansively to elevate the plunger. The handle *E* passes through a guard, *d*, on the stock *D*, and is provided with a set-screw, *G*, which acts upon the head *h*, and with an adjustable stop, *K*. The socket *C* is notched or cut out at *J*, one side of the notch being perpendicular, and the other inclined or curved, as seen at *I*. The attachment by which the button is secured to the garment is metallic, and consists of the loop *v v*, which is prepared from a piece of wire of suitable length, bent by any convenient means into a **U**-shaped loop.

In the use of the machine, the loop is placed in the aperture *O'*, with its points or ends upward, the rod *P* being so adjusted as to allow the points to project slightly above the bed *N*. The button is then inserted between the plates *M* and *L*, with its face contiguous to the bolt *S*, the cloth or garment to which the button is to be attached being inserted in the jaws of the machine between the plate *M* and bed *N*. The parts being in the position described, the jaws are now closed by pressing upon the long arm of the lever *B*, forcing the ends of the metallic loop up through the cloth, also through the holes in the button, and into the lower end of the aperture in the bolt *S* beneath the plunger *H*, the aperture in this portion of the bolt being flat or oval, to correspond with the shape of the plunger. The lever or handle *E* is then turned to the right, rotating laterally the stock *D* and bolt *S*. The bent portion of the loop being firmly held in the bed *N*, and the free ends or points projecting into the bolt *S*, as the bolt is revolved the ends of the loop will be twisted and interlocked, as best shown at

v v in Fig. 5. When the handle has nearly completed one revolution the stop K will be brought to the inclined edge I of the slot J, when, by depressing the handle, the plunger will be forced down upon the interlocked ends of the loop, and "set" or clinch the same. As the jaws are forced together, and the points of the loop enter the cloth, the bed N yields to eject the loop until it strikes the lower jaw at Q.

The rod P should be so adjusted that when the bed N comes into contact with the lower jaw the upper end of the rod P will be flush with the upper surface of the bed N. The slot in the end of the plate M should conform to the button used, the parts being so constructed and arranged that the button will always be automatically held in position to properly receive the points of the loop.

As the handle E is turned it should also be pressed downwardly, so that when it arrives at the notch J it will pass into the same down the inclined side I, by which the clinching or setting down of the ends of the loop will be performed gradually, and commenced before the twisting or interlocking of the same is entirely accomplished, which I have found to be preferable to setting down the ends after the interlocking is entirely accomplished.

It will be obvious that buttons provided with eyes, as shown in Fig. 5, instead of the ordinary perforations, may be secured to the

cloth in substantially the same manner by the use of a proper device for holding the button; also, that the plate L may be omitted, and the parts S D made integral or in one piece; also, that the mechanism may be easily adapted to be used by power, without departing from the spirit of my invention.

Having thus explained my improvement, what I claim is—

1. In a mechanism for attaching buttons to clothing, boots and shoes, &c., the combination of the plunger H, twister S, and bed N, substantially as set forth.

2. In a mechanism for attaching buttons to clothing, boots and shoes, &c., the combination of the plunger H, twister S, handle E, socket-piece C, bed N, and rod P, substantially as specified.

3. The stock D, provided with the notch J, having curved or inclined sides I, substantially as and for the purpose set forth and specified.

4. In a mechanism for attaching buttons to clothing, boots and shoes, &c., substantially such as described, the combination of the body A, lever B, socket-piece C, stock D, twister S, plunger H, spring n, lever E, plate M, bed N, and rod P, all constructed and arranged to operate substantially as set forth and specified.

SAML. W. SHOREY.
